UNITED STATES PATENT OFFICE.

FRANK M. LA BOITEAUX, OF CINCINNATI, OHIO, ASSIGNOR OF ONE-HALF
TO HENRY VARWIG, OF SAME PLACE.

FAN.

SPECIFICATION forming part of Letters Patent No. 451,873, dated May 5, 1891.

Application filed December 18, 1890. Serial No. 375,073. (No model.)

To all whom it may concern:

Be it known that I, FRANK M. LA BOITEAUX, a citizen of the United States, and a resident of Cincinnati, in the county of Hamilton and 5 State of Ohio, have invented certain new and useful Improvements in Fans, of which the following is a specification.

My invention relates to improvements in fans.

10 Its object is to impart a reciprocating rotary motion to the motor or to the fan-shaft bearings, whereby the motor, when placed against the wall or in a corner of a room, will deliver the force of the blast from the 15 fan-blades alternately to all parts of the room.

The invention consists in pivotally mounting the motor upon its stand or support and providing certain attachments, which will cause the motor to vibrate upon its support.

20 I have shown in my pending application, Serial No. 354,213, filed June 4, 1890, means for imparting a continuous rotary motion to the motor carrying the fan-shaft bearings, which delivers the blast from the fan successively to all parts of the room when the 25 motor is located centrally in the room; but as it is not always convenient to so locate it my present invention provides for an equal distribution of the air to all parts of the room 30 when it is found convenient to place the fan against one of the side walls or in a corner of the room.

I will first describe my invention and its mode of operation, referring for clearness of 35 description to the accompanying drawings, in which like parts are indicated by similar reference-letters wherever they occur throughout the various views, after which I will particularly refer to and point out in the claims 40 the parts and combinations which I desire to cover by Letters Patent as the law requires; but as I am the first one to devise means for the accomplishment of the result attained by my invention, I desire it to be understood 45 that I do not limit myself to the specific features shown and described.

Referring to the drawings, Figure 1 is a side elevation of an electric fan-motor provided with my improvements. Fig. 2 is a 50 plan view of the base and attachments with the motor removed. Figs. 3, 4, and 5 are de-

tail views illustrating features of my attachments.

Referring to the parts, A is the base or stand, which may be of any approved form 55 or design. In the present instance it is a tripod, preferably of cast-iron, fitted centrally with a socket support or bearing a, preferably of brass.

B is a fan-motor of ordinary construction, 60 provided with a downwardly-extending pivot or spindle b to enter the socket-piece a in the stand A and support the motor, while permitting it to revolve or vibrate in a horizontal plane around its vertical axis. The piece 65 a is bored from the top downwardly with a cone-point drill, and the spindle b has its lower end cone-shaped to fit the bore in the part a.

The motor-shaft C is provided at one end 70 with a fan D. Its opposite end projects through its bearing and is tapered to bear alternately against the upper and under faces of a segmental plate E, which is supported from the base A by a rod e and a curved 75 plate-spring e', the lower end of which is secured in a notch in the upper end of the rod e by a set-screw, so that it may be adjusted to give the plate E proper inclination to receive the point c alternately upon its upper and 80 lower side. To the upper end of the spring e' the segment E is centrally secured. The rod e is adjustably secured in a socket-piece a', which is preferably cast as part of the base A. The segment E is horizontally inclined, as seen in Fig. 3, and has its ends slightly curved in opposite directions, (one up and the other down,) in order that the tapered end c of the shaft C may pass under the segment when the motor is vibrated in one di- 85 rection and over it when vibrated in the opposite direction upon its pivot b. The segment E is thus held in frictional contact with the shaft-point c, which, when revolving at a high speed, will give such impetus to the motor around its axis b as to throw the motor around some distance after the point c has left the segment. To bring the motor back and the shaft-point c again in contact with the segment, I employ the balance-spring F, 90 the inner coil of which is secured to a collar f, which passes over the spindle b, to which it

is secured by a set-screw. The outer end of the spring is bent downwardly at a right angle to enter a hole in the fixed stud a^2 . A set-screw is also employed to keep this end of the 5 spring in place. The spring is so set that its neutral point is reached when the shaft-point c is at the center of the segment E, as seen in Fig. 2. This is accomplished by turning the motor to this position while the collar f is 10 loose upon the spindle b and then tightening the set-screw. When the motor is vibrated in one direction by the shaft-point c revolving upon the upper side or face of the segment and in the opposite direction by its 15 revolving against the under side, the spring will stop it at the limit of its motion in either direction and return it in the direction of its neutral point and again bring the point c in contact with the segment, thus acting as a 20 spring-buffer to limit the oscillation of the motor and return it in the direction of the central position.

The point c may be made integral with the shaft or be made separate and fastened into 25 the end of the shaft by screw-thread connection, as seen in Fig. 4. By the latter method my improvements may be attached to any of the fan-motors now in use.

It is obvious that the arc or segment E may 30 be made to extend to nearly the limit of the path traveled by the point c and stops placed at each end, against which the pin c will strike after leaving the end of the segment and be returned by the stop against the opposite side of the segment. In this way the return-spring may be dispensed with; but this 35 would cause jarring, which the spring overcomes.

What I claim is—

40 1. In a fan-motor, the combination of the stand, the motor pivotally mounted thereon,

the motor-shaft, the fan secured upon one of the extended ends, and the fixed segmental plate E, arranged to bear with its opposite faces alternately in frictional contact with 45 the extended end of the shaft opposite the fan, and means to return said shaft in contact with the segment for the purpose of imparting an oscillating motion to the motor, substantially as and for the purpose set forth. 50

2. The combination, with the fixed base, the fan-motor pivotally mounted thereon, the extended shaft-point c , the inclined segmental spring-plate E, arranged in the path of the said point to bear alternately up and down 55 against it to impart by its frictional contact with said point a circular oscillatory motion to the motor, and a return-spring to return the said point alternately in contact with the upper and under sides of said segment, substantially as shown and described.

3. The combination, substantially as hereinbefore set forth, of the base, the motor pivotally mounted thereon, the balance-spring having its opposite ends secured, respectively, 60 to the pivoted motor and fixed base, the shaft-point c , and fixed segment E to impart by frictional contact an oscillatory movement to the motor when in motion.

4. The combination of the base A, having 70 socket a , the motor B, having central pivot b to fit said socket, the spring F, coiled around and secured to said pivot and having its outer end fixed to the base, the motor-shaft C, having the extended point c , the inclined segment 75 E, rod e , and spring e' for supporting the same in the path of the shaft-point, substantially as shown and described.

FRANK M. LA BOITEAUX.
